THERMOSTAT

Leon T. Folsom, Berkeley, and John R. Mac-
Gregor, Albany, Calif., assignors to Standard
Oil Company of California, San Francisco,
Calif., a corporation of Delaware

Application November 4, 1933, Serial No. 696,649

6 Claims. (Cl. 297—8)

This invention relates to a thermostat of the flexible metallic container type, in which the container is partially filled with a volatile liquid, and is particularly directed to a balanced or compensated form in which change in ambient or atmospheric pressure, such as may be due to change in elevation of several thousand feet, will have no effect upon the calibration or setting of the thermostat mechanism.

Heretofore, thermostats of this general type have been widely known and used, and for normal changes in ambient or atmospheric pressure variation such as may be due to weather conditions their accuracy is adequate. However, where they are used on equipment which may be subjected to abnormal changes in ambient pressure, such as would occur when travelling from sea level over a high mountain pass in a railway train, or in any sort of aircraft, the variations caused thereby are serious. The common form of this thermostat balances the vapor pressure of a volatile liquid such as butane, together with some of its vapor, enclosed in a flexible metallic container or a rigid container having a movable wall, against the pressure of the atmosphere and usually a spring or other restraining force. Obviously, the restraining effort of the spring would remain substantially constant, but the restraint due to ambient or atmospheric pressure, under the conditions of change outlined above, would not remain constant. This has been found to affect seriously the setting or calibration of the temperature control mechanism controlled by such a thermostat.

For example, assume a car heater in a refrigerator car, during sub-zero weather, and with the car loaded with perishable fruit which must not be allowed to become hotter than 35° F. or colder than 32° F. With a conventional thermostat as described above, adjusted to hold the minimum temperature at 32° F. at sea level, it will be found that the change in atmospheric pressure due to a 7000 or 8000 foot change in altitude as while crossing the Sierra Nevada or Rocky Mountains will reduce the effective setting of the thermostat by as much as 4° or 5° F., thus seriously damaging the fruit.

In order to obviate this effect of atmospheric or ambient pressure variation, a second flexible metallic container is mounted to oppose the action of the first, and this second container is filled with air or some gas which, under the operating conditions, is relatively far removed from its liquid state. In the present case, the air used is at normal atmospheric temperature and consequently is so far from its liquid state that it will

follow substantially the perfect gas laws. As a consequence, a change in ambient temperature will not change the pressure in the air filled container as rapidly as it will the pressure in the butane filled container, which latter will follow the vapor-pressure temperature relation. Thus a resultant or differential motion of the flexible or movable walls of the two containers will be obtained by a change in temperature, although it will not be as great as it would be without the balancing container.

With the movable parts of the two containers faced toward each other and acting to oppose each other by their internal pressure changes, it is only necessary to provide a substantially rigid strut between them so that the resulting motion of the strut is proportional to the ambient temperature changes alone. Variations in ambient pressure from any cause will have no effect on the net force resulting from the action of the two containers opposing each other and the motion of the rigid strut resulting therefrom, as such variations will act equally and oppositely on the movable walls of the two containers, and will be cancelled thereby.

It is an object of this invention to provide a thermostat of the flexible container—volatile liquid type which will be unaffected by any change in atmospheric or ambient pressure.

Another object is to provide a simple and effective thermostat construction which may be adjusted easily, and which has a minimum of moving parts.

Another object is to provide a balanced thermostat of this type in which two opposed bellows or movable walled containers are used, one filled with a nearly perfect gas in order to cancel out or counterbalance any variations which may occur in the pressure of the ambient fluid.

These and other objects and advantages will become apparent from the description which follows, and from the accompanying drawing, which forms a part of this specification and illustrates a preferred embodiment of the invention.

In the drawing:

Figure 1 is a front elevation of a balanced thermostat embodying this invention.

Figure 2 is a section on line II—II of Figure 1, showing the opposed movable walled metallic containers and the spring restraining and adjusting means.

Figure 3 is a section on line III—III of Figure 1, showing an application of the thermostat to a rotatable shaft which may be used to control contacts or a valve, etc.

Referring to the drawing, the numeral 10 represents a rigid box frame or body provided with opposite side plates 11 and 12. These are cut away as at 13 and 14, respectively, to allow the operating mechanism, which will be described below, to pass across the center of the frame.

Movable walled container 15, which comprises a rigid flanged shell 16 and a flexible metallic bellows 17, is mounted on plate 11 as by screws 18 at the four corners of shell 16. The inner face of flexible metallic bellows 17 is provided with a filling tube 19, sealed by soldering at 20, and has a tube protecting shield or cylinder 21. The outer edge of bellows 17 is sealed to shell 16 as by soldering at 22. In this example, the container 15 is partially filled with butane 23 so that it contains both liquid and butane vapor 24 (not shown). Butane is described in this example, inasmuch as its vapor pressure at 32° F., at which range this particular thermostat is intended to operate, is substantially 14.7 lbs. per sq. inch absolute or atmospheric pressure at sea level. This choice relieves the container of excessive pressure and strain at its operating point which is desirable.

Movable walled container 25 is similar in construction to container 15, with a rigid flanged shell 26, and a flexible metallic bellows 27, the shell fastened to plate 12 with machine screws 28. The bellows 27 is similarly provided with a filling tube 29 which has a protecting shield 30, and is joined to shell 26 by soldering as at 31. This container 25, however, is filled with dry air 32 at substantially atmospheric pressure. While air is used in this example, some other gas which follows a substantially different temperature-pressure law than the liquid and vapor in container 15 could also be used, depending upon the circumstances under which the device is to operate.

A connecting strut 33 extends between the inner faces of metallic bellows 17 and 27 and is recessed at each end to fit over the shields 21 and 30, which serve to center the strut. Approximately midway between the bellows is a groove 34 in strut 33 in which a crank arm 35 on control rod 36 is adapted to be received. In this example the rod 36 is provided with a restraining spring 37 which lies between a small stud 38 on plate 12 and an arm 39 on rod 36, to hold crank arm 35 against one shoulder of groove 34, as shown. Spring 37 may also serve to open or close the valve, contact mechanism, etc., (not shown) which may be mounted on the upper end of rod 36 and which is to be actuated by this thermostat. The remainder of groove 34 may conveniently provide a lost motion element to prevent undue force being exerted upon this valve, etc., in case of high ambient temperatures while the thermostat is out of service.

Rod 36 may be supported and guided at its lower end by a ball bearing 40 in bearing cup 41 on lower connecting member 42 of frame 10. An upper bearing 43 of any desired form may be provided for rod 36 in the upper connecting member 44 of frame 10.

In order to provide a restraining force against which the containers 15 and 25 may operate, a spring 45 is placed between the inner face of metallic bellows 27 and an adjusting lever 46 which is adjustably held at one end by screw 47 secured to side plate 12, and which bears at its opposite end against an operating temperature adjusting cam 48. Lever 46 is centered and held 75 from transverse displacement by a guide member

49 extending inwardly from side plate 12 and passing through a slot 50 in the lever.

The precise operating temperature setting of the thermostat is accomplished by cam 48 mounted on shaft 51 and bearing against the free end of lever 46. Shaft 51 passes through bearing 52 in the front of frame 10 and has an adjusting and temperature indicating arm 53 on its outer end. Arm 53 moves over the face of the calibrated semi-circular dial plate 54, and is provided with a recessed spring 55 which urges ball 56 outwardly to seat in any one of the spaced recesses 57 in dial plate 54, so that any given temperature setting will be maintained in spite of shocks and jars.

The initial or calibrating temperature adjustment of the thermostat is made by screw 47 acting on the outer end of lever 46. This gives the approximate temperature at which the spring restrained balanced flexible bellows 17 and 27 will move strut 33 to actuate the control valve or the like (not shown) through the medium of crank 35 on rod 36. The exact temperature adjustment is made by moving arm 53 which controls cam 48 to give the delicate and accurate changes in the thrust of restraining spring 45 which determines the precise operating position of the control mechanism.

It is obvious that other combinations of fluids could be utilized in the two opposed flexible containers of this device, depending on the conditions under which the thermostat is to be operated. The essential feature of the invention, however, appears to reside in the provision of two such opposed containers, with dissimilar fluids therein whose temperature-pressure characteristics are such that one will respond both to ambient pressure and ambient temperature changes, while the other will respond substantially only to ambient pressure changes, so that the ultimate result will be a response only to ambient temperature changes by a resultant motion of the movable walls of the containers.

Although a specific construction embodying this invention has been described and illustrated, it is understood that the invention is not limited to that arrangement, and all such modifications and changes as come within the scope of the following claims are embraced thereby.

We claim:

1. A thermostat of the type described, comprising two spaced flexible containers, the flexible portion of both of said containers being exposed to the ambient medium, a fluid medium responsive to ambient temperature and pressure changes sealed in one container, a fluid medium responsive to ambient pressure changes sealed in the other container, and operating means responsive to the resultant movement of the flexible walls of said containers due to a change in ambient temperature.

2. A thermostat of the type described, comprising two spaced sealed containers each having a movable wall exposed to the ambient medium, a volatile liquid and its vapor in one container, a normally fixed gas in said other container whereby it is responsive substantially solely to ambient pressure, and operating means responsive to the resultant movement of the movable walls of said containers due to a change in ambient temperature.

3. A thermostat of the type described and adapted to be immersed in a fluid whose temperature is controlled, comprising two spaced sealed containers each having a movable wall

exposed to said ambient fluid, one of said containers being filled with the said fluid in which the thermostat is to be immersed, said other container being filled with a fluid whose pressure-temperature characteristic is appreciably different from said first named fluid, and operating means responsive to the resultant movement of the movable walls of said containers due to a change in ambient temperature.

- 5 10 4. A thermostat of the type described, comprising two spaced sealed containers each having a movable wall exposed to the ambient medium whose temperature is to be controlled, a volatile liquid and its vapor in one container, a normally fixed gas in said other container, resilient means opposing a movement of one of said movable walls, and means rigidly connecting said movable walls and responsive to a resultant movement thereof due to a change in ambient temperature.
- 15 20 5. A thermostat of the type described, comprising two spaced sealed containers each having a movable wall exposed to the ambient medium whose temperature is to be controlled, a volatile liquid and its gas in one container, a normally

fixed gas in said other container, resilient means opposing a movement of one of said movable walls, means for adjusting the restraining effort of said resilient means, and operating means connecting said movable walls and responsive to a resultant movement thereof due to a change in ambient temperature.

6. A thermostat of the type described, comprising two spaced sealed containers each having a movable wall exposed to the ambient medium whose temperature is to be controlled, a volatile liquid and its gas in one container, a normally fixed gas in said other container, resilient means opposing a movement of one of said movable walls, means for adjusting the restraining effort of said resilient means, and means connecting said movable walls and responsive to a resultant movement thereof due to a change in ambient temperature, said last named means adapted to be connected to an ambient temperature controlling device, whereby said temperature may be maintained in a definite range.
